UNITED STATES PATENT OFFICE.

WILLIS J. PERKINS, OF GRAND RAPIDS, MICHIGAN.

SHINGLE-SAWING MACHINE.

SPECIFICATION forming part of Letters Patent No. 325,693, dated September 8, 1885.

Application filed September 18, 1884. (No model.)

To all whom it may concern:

Be it known that I, WILLIS J. PERKINS, of Grand Rapids, in the county of Kent and State of Michigan, have invented certain new and useful Improvements in Shingle-Machine Carriages; and I do hereby declare the following to be a full, clear, and exact description of the invention, such as will enable others skilled in the art to which it appertains to make and to use the same.

My invention relates to an improvement in shingle-machine carriages, and more particularly to carriages adapted to use in connection with a hand-feed shingle-machine. The operator, standing in front of a shingle-machine, pushes the carriage and shingle-bolt from him over the saw until the shingle is severed from the bolt, and then draws back the carriage and remaining portion of the bolt, the shingle falling from the point where it was entirely severed from the bolt into a suitable spout or receptacle. An operator will go through this motion of advancing and returning the carriage from twenty-five thousand to fifty thousand times per day, the number varying according to his skill. It follows, therefore, that any reduction in the weight or friction of the carriage is a matter of the highest importance, both in saving the strength and increasing the efficiency of the operator.

The object of my present invention is to provide a shingle-machine carriage of minimum weight and maximum strength; a further object being to provide bearings of such construction that the sliding friction shall be reduced to minimum; a further object being to provide improved mechanism for operating the movable dog, and improved fittings for uniting the several parts of the carriage; a further object being to provide simple means for adapting my new style of carriage to machines fitted with the old style.

With these ends in view my invention consists in certain features of construction and combinations of parts, as will be hereinafter described, and pointed out in the claims.

In the accompanying drawings, Figure 1 is a top plan view of the carriage and ways. Fig. 2 is a view in side elevation, and Figs. 3, 4, 5, 6, 7, 8, and 9 are detached enlarged views of parts.

A A represent a set of carriage-ways of the

form hitherto in use, as represented in Letters Patent No. 272,316, granted to me February 13, 1883.

B B' represent the ways adapted to receive my improved carriage, and are shown in the accompanying drawings, of such form as will admit of their being readily attached to the ways A A. The way B is provided along its inner edge with a horizontal bearing-surface, b. An upright surface, b', extends along the outer edge of the surface b, and a second horizontal surface, b'', terminates the upright surface b'. A metal plate, C, L-shaped in cross-section, has one edge bolted on the surface b'', while the opposite edge extends downwardly to a point a short distance above the inner edge of the way B, the plate C thus forming, with the way B, a horizontal channel L-shaped in cross-section. The way B' is provided on its inner face with a horizontal groove or channel, b', about one-half inch in depth. Longitudinal ribs z z' are formed along the upper inner edges of the ways to guard the head-block and dog against injury in placing the bolt.

The carriage-frame consists of two side rails, D D', a stationary dog, E, and a movable dog, E', constructed of steel tubing—in the present instance, about one inch in diameter. The use of steel tubing in this construction is an important feature of my invention, as its great tenacity, combined with hardness, admits of its being made lighter than iron tubing and yet being stiffer and more durable. The fittings which connect the stationary dog E with the ends of the side rails consist of a tubular elbow, one branch of which, e, fits within the end of the dog E, and the other branch of which, d, fits over the end of the side rail, D. Figs. 3 and 4 represent an end view and top plan view, respectively, of one of the fittings above mentioned. A perforation, e', is made through the branch e and dog E, which receives a rivet or bolt for securing the fitting rigidly to the dog. A perforation, d', is made through the branch d and side rail, D, in such a position that when the fitting is secured to the side rail by a bolt, d', passing through said perforation, the fitting will lie in close proximity to the face of the way B'. A second perforation, d', of the same diameter as the perforation d', is made through the rail D, about one inch from d

to admit of adjusting the dog E nearer the dog E' when sawing from shorter bolts. The branch d is provided with a slit, d', on its side which admits of its being closely clamped on the rail D by the draw-bolt d''. The sliding bearings F and F', which move in the channels formed in the ways B' and B, respectively, are formed integral with or firmly secured centrally to the ends of short tubes f, which latter are constructed to fit snugly within the ends of the rails D and D', and are rigidly secured therein by rivets or other suitable means. The bearings F consist of short bars which bear against the upper and lower sides of the channel b³, but have no lateral bearing within the channel. The bearings F' are L-shaped in cross-section and fit within the L-shaped channel formed by the way B and plate C secured thereon. They bear downwardly on the surface b, upwardly against the edge of the plate C, and inwardly against the face b⁴ of the L-shaped plate C. The latter bearing is directly opposed to the drag caused by the saw-thrust. The outer portions of the bearings F' are provided with recesses f'', which render the bearings lighter, and are valuable as oil-receptacles. Figs. 5 and 6 represent side, end, and top plan views of the bearings F and F', respectively. A set of steel holding-teeth G is secured to the stationary and the movable dog by means of blocks g, the blocks being hollowed out on the face in contact with the dog, to conform to the circular shape of the same, and having flat projections g' at the point where they grip the tooth-bar g''. The blocks g are bolted or riveted to the dogs. The movable dog E' is attached to the side rails, D D', by means of sleeves H, which fit and slide on the side rails, said sleeves being provided with short tubular projections h, formed integral therewith or rigidly secured thereto, which projections fit within the ends of the dog E' and are rigidly secured thereto. By this construction the movable dog E' 45 serves the purposes of a girder and renders a stationary end beam unnecessary. The sleeves H are further provided with upright lugs K, rigidly secured thereto, which form bearings k for the tubular operating-rod L. The rod 50 L is bent at right angles at its front end and provided with an operating-handle, l. The rod L is further provided just outside of the lugs K with downwardly-projecting arms M, rigidly secured thereto. The lower ends of 55 the arms M are pivotally secured to links m, the links being pivotally secured to the side rails at m'.

From the above construction it will be observed that when the handle l is pressed downwardly the sleeves and dog connected thereto will be forced inwardly toward the stationary dog. The motion is perfectly simple and the construction such that the side rail is not extended in length beyond absolute necessity, the weight of the carriage thereby reduced and its strength increased.

My improved carriage, constructed in the

manner herein described, weighs less than my old-style carriage of the same carrying capacity, while the metal of which it is made is disposed in such form that a maximum strength is obtained and the resistance from friction reduced to a minimum.

It is evident that slight changes may be made in the form and arrangement of the several parts described without departing from the spirit and scope of my invention—for example, the introduction of a toothed sector in the place of arm M, the sector engaging a rack-bar secured to the side rails; hence I do not wish to limit myself strictly to the construction herein set forth; but,

Having fully described my invention, what I claim as new, and desire to secure by Letters Patent, is—

1. The combination, with the sides of a shingle-machine carriage and a stationary dog connected therewith, of a movable dog consisting, essentially, of a tube or pipe provided with holding-teeth.

2. The combination, with the sides of a shingle-machine carriage and a movable dog connected therewith, of a stationary dog consisting, essentially, of a tube or pipe provided with holding-teeth.

3. The combination of the sides of a shingle-machine carriage, a stationary dog, and a movable dog, each of said dogs consisting, essentially, of a tube or pipe provided with holding-teeth, substantially as set forth.

4. In a shingle-machine carriage, the combination, with two sides and a stationary dog secured thereto, of a movable dog forming an end girder for the sides.

5. In a shingle-machine carriage, the combination, with sides and a stationary dog, of a movable dog provided at its opposite ends with sleeves, which latter encircle the sides of said carriage, substantially as set forth.

6. In a shingle-machine carriage, the combination, with sides and a stationary dog secured thereto, of a movable dog forming an end girder of said carriage, and provided at opposite ends with sleeves which embrace the side rails, substantially as set forth.

7. The combination, with a shingle-machine carriage consisting, essentially, of two sides and a stationary and a movable dog, of a rod connected to and moving with the movable dog, arms attached to the rod, and links connecting the arms with the sides of the carriage, substantially as set forth.

8. The combination, with a shingle-machine carriage consisting, essentially, of two sides and a stationary and a movable dog, of a rod journaled to the movable dog and connected by one or more links to the carriage, whereby the rod is carried backward and forward with the movable dog, substantially as set forth.

9. The combination, with a shingle-machine carriage and a movable dog having boxes or bearings, which rest and slide on the sides of the carriage, of lugs secured to or formed integral with said dog or its bearings, and a

bell-crank operating-rod journaled in said lugs, substantially as set forth.

10. The combination, with the sides of a shingle-machine carriage, of two sets of sliding bearings secured thereto, one set of said bearings being plain flat bearings, while the other set is L-shaped or its equivalent in cross-section, for the purpose of taking all the side-thrust of the carriage, substantially as set forth.

11. The combination, with the sides of a shingle-machine carriage, of a stationary dog, fittings secured within the ends of the dog, and provided with sleeves for embracing the sides of the carriage, said fittings being secured to the dog and to the sides of the carriage.

12. In a shingle-sawing machine, the com-

bination, with a machine-frame, a saw, and a longitudinal rib or ribs secured to the frame and extending upwardly above the carriage, of a carriage mounted on the frame, the sides of said carriage being parallel with the rib or ribs, substantially as set forth.

13. A shingle-machine carriage consisting, essentially, of two sides and two ends, the latter forming end girders and dogs, substantially as set forth.

In testimony whereof I have signed this specification in the presence of two subscribing witnesses.
